UNITED STATES PATENT OFFICE.

LAURENCE E. JONES, OF LIBERTY, MISSOURI.

AUTOMOBILE SIGNAL DEVICE.

1,282,430.

Specification of Letters Patent. Patented Oct. 22, 1918.

Application filed February 11, 1916. Serial No. 77,626.

To all whom it may concern:

Be it known that I, LAURENCE E. JONES, a citizen of the United States of America, and a resident of Liberty, county of Clay, and 5 State of Missouri, have invented certain new and useful Improvements in Automobile Signal Devices, of which the following is a specification.

The main objects of this invention are to 10 provide an improved signal apparatus arranged so as to indicate to drivers of other vehicles, at the rear of the one on which the signal is mounted, any proposed change in the course or progress of such vehicle; 15 to provide an improved construction and arrangement of the signaling mechanism embodying one signal for indicating a change in the progress of the vehicle and another signal for indicating the direction of the 20 change; to provide improved means for independently controlling said signals; to provide an improved construction of the signs and their arrangement in the housing; and to provide improved means for insuring the 25 proper registration of the signs with the sight opening or window in said housing.

An illustrative embodiment of this invention is shown in the accompanying drawings in which:

30 Figure 1 is a front elevation of the signal device showing the signals shifted to expose certain of the signs.

Fig. 2 is a left hand end view of the same with the end cap removed.

35 Fig. 3 is a similar view of the opposite end.

Fig. 4 is an enlarged detail of one of the armatures and its connection for operating the signal member.

40 Fig. 5 is a similar view of the armature for operating the other signal member.

Fig. 6 is a diagrammatic view illustrating the arrangement of the circuits and the switch controlling means for the signals.

45 Fig. 7 is a sectional view taken on the line A—A of Fig. 1.

Fig. 8 is an enlarged development of the sign which indicates the direction of a change in the course of the vehicle.

50 Fig. 9 is a similar view of the other sign which indicates a change in the progress of the vehicle.

In the construction shown in the drawings, the device comprises a casing 1 within 55 which are rotatably mounted signal members or drums 2 and 3, having signs on the

periphery thereof which, through the rotation of the members, are adapted to be moved into position to be exposed through windows or openings 4 and 5 formed in the 60 casing. The signal members 2 and 3 each comprise spider wheels 6 and 7 rigidly secured to the respective shafts 8 and 9 which are journaled in bearings formed on the 65 bars 10 extending transversely across the casing 1.

The signs 11 and 12 on the respective signal members are in the form of transparent or translucent material, such as glass or celluloid. The sign 11 is divided into two 70 sections 13 and 14, and the sign 12 is divided into three sections 15, 16 and 17. On the respective signs the sections 13 and 15 are perfectly plain and may be made a conspicuous color, such as red or green. The sections 75 14, 16 and 17 are preferably made white and the characters thereon made red so that they will be conspicuous in the daylight as well as night when illuminated from the interior. The section 14 contains suitable 80 characters to indicate a change in the course or progress of the vehicle. In the construction herein shown, the word "Stop" is used. The sections 16 and 17 have thereon characters, such as arrows, for indicating 85 the direction of change in the course of the vehicle.

The mechanism for operating the signal member 2 comprises a rocker arm 18, pivoted at 19 in the casing 1 and having a rack 90 20 formed on the other end thereof which meshes with a pinion 21 rigidly connected to the shaft 8. A spring 22 embraces the shaft 8 and has one arm thereof engaging a shoulder 23 on the rocker arm 18 and the 95 other arm secured to the hub of the adjacent spider-wheel 6. This spring acting upon both the arm 18 and the signal member 2 normally urges the signal member into position to display the plain section 13 at the window 4. The rocker arm 18 also constitutes an armature adjacent to which are arranged a pair of electro-magnets 24 so as to actuate the same and cause the rack 20 and pinion 21 to rotate the drum to move the 100 section 14 of the sign into registration with the window 4.

Similar mechanism is provided for the signal member 3. A combined rocker arm and armature 25 is pivoted at 26 to the casing 1 and has a rack 27 formed on the end thereof meshing with a pinion 28 connected 110

to the shaft 9 which supports the signal member 3. A spring 29 embraces the shaft 9 and has the two arms thereof crossed and engaging opposite sides of a shoulder 30 carried by the rocker arm 25 whereby it is normally urged to shift the signal 2 into position to display the plain section 15 at the window 5. A pin 31 is secured to the hub of the pinion 28 and has the inner end thereof bent to provide a finger 32 located between the arms of the spring 29 so as to engage one or the other of said arms for facilitating the return of the signal member 3 to its normal position. Two sets of magnets 33 and 34 are located at opposite sides of the armature 25 for the purpose of actuating the same in opposite directions and causing one or the other of the sections 16 and 17 of the sign 12 to be exposed through the window or opening 5.

The magnets 24, 33 and 34 have wires leading therefrom to suitable binding posts on the casing 1 from which wires lead to the switch controlling means.

Separate switch controlling means are provided for each of the signal members. For the signal member 2 a switch 35 is located in position to be actuated by the brake or clutch pedal 36 of the vehicle and is normally urged into its open position so that the circuit to the magnets 24 is normally open, thereby allowing the signal to occupy its normal position. The switch controlling means for the signal member 3 comprises a pair of contacts 37 and 38 located on a stationary part 39 of the steering mechanism 40 of the vehicle and connected to the respective magnets 33 and 34. A switch arm 41 is pivoted to the stationary part 39 and is normally urged by a spring 42 to occupy a neutral position between the contacts 37 and 38. A pair of shoulders 43 and 44 carried by the movable part of the steering mechanism 40 are arranged on opposite sides of the switch arm 41 so as to engage the same when the steering mechanism is operated and shift the switch arm in respectively opposite directions for the purpose of causing it to engage one or the other of the contacts 37 and 38.

The signal members 2 and 3 being spaced apart axially, as more clearly indicated in Fig. 7, provides a space between them whereby a light 45 is attached to the casing 1 so that by virtue of the open ends of the members, the sections registering with the windows 4 and 5 are illuminated.

In order to insure proper registration of the sections 14, 16 and 17 with the windows 4 and 5 respectively, suitable coacting shoulders are arranged on the signal members 2 and 3 and the casing 1 for this purpose. For the signal member 2 this comprises a pin 48 carried by one of the spider wheels 6 and arranged to engage shoulders 49 and

50 suitably positioned within the casing 1. Likewise, a shoulder or pin 51 is located on one of the spiders 7 so as to engage shoulders 52 and 53.

The signal device is designed for attachment to the rear of an automobile or other vehicle so as to be in conspicuous view of the drivers of vehicles following, so that they may be notified of any change in the course of the vehicle and act accordingly. It is intended that the license tag 46 should be suspended from the casing 1, there being an opening 47 in the bottom of the casing so that the tag is illuminated, as will be obvious.

The operation of the device shown is as follows:

Normally, when the vehicle is traveling straight ahead, the switch mechanisms controlling the magnets 24, 33 and 34 occupy positions which leave the circuits open so that the signal members 2 and 3 occupy their normal positions and the plain sections 13 and 15 are exposed to view at the windows 4 and 5 respectively. Upon approaching a crossing where it becomes necessary to stop, the operator upon shifting the foot pedal 36 closes switch 35 and thereupon energizes the magnets 24. The attraction of the armature 18 shifts the signal member 12 so that the section 14 bearing the word "Stop" is exposed through the window 4 which serves as a warning to any vehicles following. The release of the foot pedal 36 will break the circuit to the magnets 24, whereupon the signal 2 will return to its normal position, exposing the plain section 13 at the window 4. If it is the intention of the driver to turn, the corresponding operation of the steering wheel causes the arm 41 to be shifted to engage one or the other of the contacts 37 and 38 so that the circuit will be completed to one or the other sets of the magnets 33 and 34. The corresponding shifting of the armature 25 rotates the signal member 3 and moves one or the other of the sections 16 or 17 into registration with the window 5. The driver at the rear is thereupon notified that the vehicle is turning left or right, as the case may be, and he is warned to act accordingly. As soon as the vehicle has completed the turn, the switch 41 is shifted to its neutral position so that the circuit is broken to the magnets 33 and 34 and the armature 18 is shifted by the spring 29 into its normal position.

Although but one specific embodiment of this invention has been herein shown and described, it will be understood that numerous details of the construction shown may be altered or omitted without departing from the spirit of this invention as defined by the following claims.

I claim:

1. A vehicle signal device comprising a

- casing having a pair of windows therein, a pair of drums rotatably mounted within said casing and spaced apart axially, a sign on one of said drums adapted to register with one of said windows for indicating that the forward movement of the vehicle is to be arrested, signs on the other said drum spaced apart peripherally and adapted to be separately exposed through the other said window so as to indicate the direction in which the vehicle is to turn, means normally urging said drums to conceal said signs, mechanism for individually shifting said drums to expose said respective signs, and illuminating means arranged in said casing so as to make said signs visible through said windows.
2. A vehicle signal device comprising a casing having a pair of windows therein, a pair of drums rotatably mounted within said casing and spaced apart axially, a sign reading "Stop" arranged on one of said drums adapted to register with one of said windows for indicating that the forward movement of the vehicle is to be arrested, signs in the form of oppositely disposed arrows arranged on the other said drum spaced apart peripherally and adapted to be separately exposed through the other said window so as to indicate the direction in which the vehicle is to turn, means normally urging said drums to conceal said signs, mechanism for individually shifting said drums to expose said respective signs, and a single illuminating means arranged in said casing between said drums whereby said one illuminating means serves to illuminate both of said drums and the respective windows through the open ends of said drums.
- Signed at Kansas City, Mo., this 8th day of Feb., 1916.

LAURENCE E. JONES.
